COMBINED VALVE AND FLOAT FOR A COMMODE

Shirley McLarty, 417 Blanning, Dallas, Tex. 75218
Filed Sept. 14, 1965, Ser. No. 86,991

Term of patent 14 years

(Cl. D91—1)

FIG. 1 is a perspective view of a combined valve and float for a commode showing my new design.

FIG. 2 is a fragmentary side elevational view of the device of the design shown in FIG. 1.

The rear and side not shown are the same, respectively, as the front and side shown, except that the small hole in the float and the fitting on the lower cylindrical element appear only where shown in FIG. 1.

The vertical guide upon which the small diameter element is placed has an "I" cross-sectional configuration throughout its height as indicated by the lowermost portion thereof in FIG. 1.

I claim:

The ornamental design for a combined valve and float for a commode, as shown and described.
